5 Claims. (Cl. 178—88)

1

This invention relates to telegraph receivers. A telegraph receiver must in general comprise a means for timing the periods occupied by the successive elements of the code. This is generally done by means of rotating mechanical parts and great accuracy of manufacture is necessary for these parts.

According to one feature of the present invention there is provided a receiver for a telegraph code comprising a time base derived by electric discharge services for timing the intervals occupied by the elements of said code, and means for determining the kind of elements received in each of said intervals.

According to another feature of the invention there is provided a receiver for a telegraph code comprising means for generating an evenly spaced series of electric impulses, means for timing the intervals occupied by the elements of said code by the intervals between said impulses and means for determining the kind of element received in each of said intervals.

The invention will be described as applied to the reception of start stop teleprinter codes and as so applied a receiver according to one feature of the invention comprises an electric impulse generator for generating an evenly spaced series of impulses, means responsive to the start element of a code signal for starting said impulse generator into operation, and means for timing the intervals occupied by the elements of said code by the intervals between said impulses and means for determining the kind of element being received at the middle of each of said intervals.

Preferably the receiver according to the invention comprises a chain of gas filled electric discharge devices which are caused to be rendered conducting sequentially by sequential impulses and in the case of a receiver for start stop teleprinter codes the electric impulse generator that is started into operation by the receipt of the start element of a code delivers an impulse to the electric discharge device corresponding to the start element of the code after a delay equal to half the period of time allotted to the start element. Each electric discharge device causes the succeeding device to become conducting when the next impulse is applied so that these successive devices become conducting at the midpoint of the successive elements and the time interval to be occupied by the signal is determined by the chain of devices.

The invention has been devised primarily for use in the electric signalling system claimed in

2

copending U. S. patent application Ser. No. 744,009. In this system the closure of contacts individual to different pieces of apparatus at one or more substations causes the transmission of pre-determined teleprinter codes individual to the particular contacts to a supervisory station where a device individual to the contacts at the transmitter is operated upon the receipt of the predetermined code signal. The invention accordingly provides a receiver for predetermined telegraph codes comprising for each said code a chain of gas filled electric discharge devices, one for each element of the code, means for setting the successive devices of each chain so as to cause each to be rendered conducting only upon the simultaneous occurrence of the preceding device in the chain being conducting and an element of the required kind being received means for causing successive elements of the code to be applied to successive devices in the chain and means operative upon the last device in the chain becoming conducting to cause the receipt of the code to become operative.

It is preferred that the codes used in such a system should be chosen so that the earlier occurring elements are as far as possible common to a plurality of codes and the several chains of electric discharge devices are combined to the extent that devices representing elements common to a plurality of codes are provided and are connected so as to be common to the like plurality of chains of such devices.

This principle is readily extended to provide reception of the full number of codes possible. Thus for a start-stop teleprinter code using five code elements, thirty two different combinations are possible. There are thus thirty two chains of electric discharge devices required but the number of such devices is reduced by arranging one such device for the start element which is common to all the combinations. This device is connected to a pair of devices for the second element of the code, one for a marking element and one for a spacing element. The start becomes conducting in response to the start element and impresses on each device of the said pair of a potential tending to make it conducting. When the first code element is received it impresses a second potential on that one of the pair that corresponds to the kind of element. The two potentials added together make one of the pair conducting. Each device of this pair is connected to two further devices for the next element and so on in geometrical progression. In this way any particular code received progresses along only

one chain of electric discharge devices and only one device corresponding to the last element of the code combination becomes conducting and indicates the receipt of that particular code combination.

Although this completed chain of electric discharges in one sense times the telegraph code, it is preferred to use a separate means for this purpose and in the preferred form this separate means consists of a separate pilot chain of electric discharge devices rendered conducting sequentially by the application thereto of an evenly spaced series of impulses.

The invention will be better understood from the following description taken in conjunction with the accompanying drawings in which:

Figs. 1 and 2 together form one circuit diagram, Fig. 1 showing the pilot chain of tubes and a receiver for one predetermined code and Fig. 2 the circuit of the impulse generator and the telegraph relays receiving signals from the line;

Fig. 3 shows diagrammatically how tubes of the receiver may be arranged for a certain number of code combinations; and

Fig. 4 shows diagrammatically the arrangement of tubes of the receiver for a complete 5-unit code receiver.

Referring to the drawings and first to Fig. 1 there are shown two trains of three electrode gas-filled cold-cathode tubes. The first or pilot chain consists of seven tubes 1 . . . 7, one for each element of the code. These tubes are connected each to the next in the chain in a manner similar to that shown in U. S. Patent No. 2,421,005, but modified in an important respect.

All the tubes are similar so that only one need be referred to in detail. Tube 1 comprises an anode 8, a control electrode 9 and a cold cathode 10. In order to render the tube conducting the gap between the control electrode 9 and the cathode 10 must be ionised and a positive potential must be applied to the anode 8 with respect to the cathode. So long as this potential is 130 volts or more, the minimum ionisation current produced by a voltage of about 70 volts between control electrode 9 and cathode 10 is sufficient to cause current to flow between anode 8, and cathode 10. As the potential applied between anode and cathode diminishes below 130 volts, the ionisation current between control electrode 9 and cathode 10 and consequently the potential applied between them, that is needed to render the tube conducting, increases rapidly.

When the tube 1 is conducting, current flows through resistances 11 and 12 between cathode 10 and earth. In U. S. Patent No. 2,421,005 the resistances between the cathode and earth were so proportioned as to give a voltage drop of about 35 to 40 volts thereacross and the cathode was connected directly to the control electrode of the succeeding tube (such as tube 2). The source of potential 13 for the anodes of tubes 1 . . . 7 is derived ultimately from the mains and if the mains voltage falls, the voltage applied to the anode of tube 2 falls and the nominal voltage applied to its control electrode from the cathode circuit of tube 1 also falls.

In the present circuit therefore, resistances 11 and 12 are proportioned to give a voltage drop of twice that previously provided between cathode and earth and the junction point of these resistances is connected (over a resistance 14 as previously) to the control electrode of tube 2. The fall in the nominal voltage applied to the control electrode 9 of tube 2 due to a given fall in

mains voltage is then less than before. Moreover the voltage drop between the source 13 and the anode of tube 1 is reduced so that tube 1 is more easily extinguished by tube 2 becoming conducting. The voltage drop across tube 1 when conducting is about 70 volts so that the anode of tube 1 is about 140 volts above ground potential. As the anode of tube 2 is connected directly to the anode of tube 1 and the cathode of tube 2 is at earth potential when the tube is not conducting, the voltage applied between the anode and cathode of tube 2 is held, even if the mains voltage varies, above the value at which minimum potential difference between control electrode and cathode will cause the tube to become conducting.

In the initial condition of the circuit of Figs. 1 and 2, tube 1 is conducting and a potential difference is impressed from its cathode circuit between the control electrode and cathode of tube 2. This potential difference is about 35 volts, which is insufficient to cause the tube to become conducting, the potential difference required for this purpose being about 70 volts.

The incoming line 15 Fig. 2 is connected over windings of telegraph relays 16 and 17 to ground. As in the normal, non-signalling condition of line 15 marking potential is impressed thereon at the transmitting station, the contacts 18 and 19 of these relays are in marking position. The cathode of tube 1 Fig. 1 is connected over a conductor 20 to the marking contact of contacts 19 and thus through a condenser 21 and ground. Condenser 21 is thus kept charged.

Fig. 2 shows the circuits of an impulse generator and the means by which it is started into operation. The impulse generator comprises two pentodes 22 and 23 connected in well known manner as a multivibrator. The anode potentials are supplied from a source stabilised by means of a neon-tube stabiliser 24. The normal grid potentials are adjusted by means of potentiometers 25 and 26, the sliding contact on 25 serving to adjust the frequency and that on 26 the relative times of operation of the two tubes. The impulses are derived from the grids of pentodes 22 and 23, these grids being connected over respective condensers to the grids of triodes 27, 28 so that the changes of potential on the grids of pentodes 22 and 23 being thus differentiated to produce positive impulses on conductors 29 and 30 connected to the anodes of those triodes.

The multivibrator is held in non-operating condition by the cathode of tube 22 being normally connected to positive potential. A three electrode cold cathode tube 31 is normally conducting and current therefore flows through resistance 32 connected to the cathode thereof, the positive end of this resistance being connected to the cathode of pentode 22. There is a second three electrode cold cathode tube 33, which is normally non-conducting, the anode of which is connected over a condenser 34 to the anode of tube 30.

The spacing contact of contacts 19 is connected to earth over the primary of a step-up transformer 35, the secondary of which is connected to the control electrode of tube 33. When therefore the start element of a teleprinter code combination is received and contacts 18 and 19 of relays 16 and 17 change over to spacing position, condenser 21 is discharged through the primary of transformer 35. The resultant potential across the secondary of this transformer 35 is impressed between control electrode and cathode of tube 33 and is sufficient to ionise the gap between those

electrodes and the tube 33 becomes conducting. The interconnection of the anodes of tubes 31 and 33 through condenser 34 results in tube 31 becoming non-conducting and the disappearance of the positive bias on the cathode of pentode 22.

The positive bias on the cathode of pentode 22 has previously held this pentode from passing current and the multivibrator is therefore normally in the position in which anode current in pentode 23 is a maximum. When the positive potential on the cathode of tube 22 is removed the grid of that tube becomes positive with respect to the cathode and the tube 22 passes current and the anode current rapidly rises to a maximum and remains so until the condenser connecting the anode of pentode 22 to the grid of pentode 23 has discharged. Pentode 23 then passes current and there is a sudden drop in the potential of the grid of pentode 22. This sudden drop in potential is differentiated by condenser 36 and a positive pulse is created on conductor 29 connected to the anode of tube 21. The period of the multivibrator may be set so that this pulse occurs 10 milliseconds after the commencement of its operation and thus at the mid-point of the period of 20 milliseconds for the start element of the incoming signal (for a teleprinter signalling speed of 50 bauds).

Conductor 29 is connected to a conductor 37 which in turn is connected over an individual condenser resistance combination to the control electrodes of tubes 2 . . . 7. The value of the potential thus impressed on these control electrodes is insufficient to ionise the gap between control electrode and cathode of any of the tubes, but added to the potential impressed on the control electrode of tube 2 from the cathode circuit of tube 1 is sufficient to cause tube 2 to become conducting.

When tube 2 becomes conducting a potential is impressed from its cathode circuit upon the control electrode of tube 3 (and also upon the control electrode of another tube to be referred to presently) and upon the next occurrence of an impulse on conductor 37, i. e. after a period of 20 milliseconds, tube 3 becomes conducting. This in turn impresses a potential upon tube 4. In this way tubes 3, 4, 5, 6 and 7 become conducting on the occurrence of successive impulses.

It should be noted that the anodes of all the tubes 1 . . . 7 are connected to positive potential over a common resistance 38, which is of such value that when a tube such as tube 2 becomes conducting the potential upon the anode of any other tube, such as 1, that is at that moment conducting is depressed below the value necessary to keep the tube conducting when only a very low potential is applied across the gap between control electrode and cathode. The consequence is that when any tube in the chain 1 . . . 7 becomes conducting the preceding tube in the chain becomes non-conducting.

The tubes 1 . . . 7 correspond to the different elements of a start-stop five unit teleprinter code. Tube 1 is a pilot tube, normally conducting and corresponding to the stop element of the code. Tube 2 corresponds to the start element of the code and tubes 3 . . . 7 to the code elements. The tubes 2 . . . 7, operated sequentially by the impulses on conductor 37, time the intervals occupied by the elements of the code, becoming conducting at the mid-points of the elements allotted to the code.

The cathode circuit of tube 7 is connected over

conductor 39 to the control electrode of a cold cathode tube 40 (Fig. 2) which control electrode is also connected to conductor 30. The impulse generator applies an impulse to conductor 30 ten milliseconds after each impulse applied to conductors 29 and 31 so that when tube 7 has been conducting for ten milliseconds tube 40 becomes conducting. The cathode of this tube 40 is connected to ground over the primary of a step up transformer 41, the secondary of which is connected to the control electrode of tube 31. The potential thus impressed, when tube 40 becomes conducting, upon the control gap of tube 31 causes that tube to become conducting. Owing to the connection between the anodes of tubes 31 and 33 over condenser 34, tube 33 becomes non-conducting. Another effect of tube 31 becoming conducting is to impress a positive potential upon the cathode of pentode 22 and so stop the impulse generator. Tube 40 is connected so as to be self-extinguishing.

The secondary of transformer 41 is connected over a conductor 42 to the control electrode of tube 1 (Fig. 1) and the impulse delivered when tube 40 becomes conducting also causes tube 1 to become conducting. Tube 1 is thereby rendered non-conducting.

So far no reference has been made to the effect of the receipt of the code elements of a signal. Fig. 1 shows a receiver for a particular code-combination. This receiver consists of five tubes 43 . . . 47 corresponding to the five code elements of a five unit teleprinter code. The anodes of all these tubes are connected together and through a resistance 48 to a positive source 49. The cathode circuit of tube 2 is connected to the control electrode of tube 43 and the cathode circuit of each of the tubes 43 . . . 46 is connected to the control electrode of the next tube in the chain in the same manner as the tubes 1 . . . 7 are connected together.

The control electrodes of tubes 43 . . . 47 are connected through individual condensers and resistances to either of two conductors 50 or 51 which in turn are connected to the spacing and marking contacts respectively of relay 46. The connections between the control electrodes of the tubes 43 . . . 47 and conductors 50 and 51 are preset in accordance with a particular code combination, in the case shown, mark, space, space, space, mark. The operation is as follows:

Tube 2 is made conducting when the start element of a teleprinter signal is received, as described above, and a potential is thereby impressed not only between control electrode and cathode of tube 3 as described above, but also between control electrode and cathode of tube 43. The second impulse on conductor 29 occurs at an interval of 20 milliseconds after the first impulse, i. e. in the middle of the interval allotted to the first code element of the received signal. Conductor 29 is connected to the moving tongue of contacts 48 and if at this moment a marking impulse is being received, so that contacts 48 are in marking position, this impulse is applied over conductor 51 to the control electrode of tube 43. The potential due to this impulse, added to the potential impressed from the cathode circuit of tube 2 causes tube 43 to become conducting. The cathode circuit of tube 43 impresses a potential on the control electrode of tube 44. If, on the occurrence of the next impulse on conductor 29, contacts 48 are in spacing position, the potential of this impulse is applied over conductor 50 to the control electrode of tube 44 and tube 44

becomes conducting and tube 43 is made non-conducting.

If, on the other hand, contacts 18 were in spacing position on the occurrence of the second impulse on conductor 29, tube 43 would not have been made conducting. In this case tube 43 would not be made conducting upon any subsequent impulse. Also if tube 43 has been made conducting because the first code element is a mark, but the second code element is also a mark so that on the occurrence of the third impulse on conductor 29 contacts 18 are in marking position, tube 44 would not be made conducting. Tube 44 will however be made conducting on the occurrence of a subsequent spacing element forming part of the code combination.

It will be clear that if the code combination received be that for which tubes 43 to 47 is set these tubes will be made conducting in succession, but that if any other code combination be received, tube 47 will not have been made conducting by the time the code combination has come to an end and the creation of impulses from the multivibrator 22, 23 has ceased. If the correct code combination has been received and tube 47 has become conducting, current flows from a point in the cathode circuit of tube 47 through a rectifier 52 in the forward direction to charge a condenser 53 in such sense as to apply positive potential upon the grid of a triode vacuum tube 54 whereby a relay 55 connected between the cathode of tube 54 and ground is operated. Relay 55 closes its contacts 56 to operate a meter 57 or other indicator. The rectifier 52 is shunted by a resistance 58 which allows the condenser 53 to discharge in about half a second.

An additional cold-cathode tube 59 is provided having its anode connected to the anodes of tubes 43 . . . 47. The control electrode of tube 59 is connected to the conductor 42, so that when, at the end of the period allotted to the receipt of a start-stop teleprinter code tube 1 is made conducting by an impulse from the secondary of transformer 41 over conductor 42, as above described, tube 59 is also made conducting. The common anode connection ensures that any of the tubes 43 . . . 47 that may then be conducting is made non-conducting. Thus the tubes 43 . . . 47 are ready for the receipt of a further code combination, whether the code combination for which they were set had, or had not been received. Tube 59 will be rendered non-conducting during the receipt of a subsequent code combination if any of the tubes 43 . . . 47 then becomes conducting.

It will be clear that as many sets of tubes such as 43 . . . 47 may be provided as there are code combinations to be received, each set being connected up so that, upon the receipt of the correct code combination a relay such as 55 will be operated.

It is however possible to choose the codes to be operative at the receiver in such manner as to reduce considerably the number of electric discharge devices required. This may be done by choosing the codes so that the earlier occurring elements are as far possible common to a plurality of codes. The several chains of electric discharge devices are then combined to the extent that devices representing elements common to a plurality of codes are provided and connected so as to be common to the like plurality of chains of such devices.

Fig. 3 shows diagrammatically how this can be done for four and eight codes respectively. Each of the circles represents a cold-cathode tube.

Those tubes that have control electrodes connected to the marking conductor 51, Figs. 1 and 2, are shown as black circles, those that have control electrodes connected to the spacing conductor 50 are shown as open circles. One arrangement of tubes for four codes is shown above the dashed line. It will be noted that the first three tubes 60, 61, 62 arranged for mark, space, space as the first three elements are common to all four codes.

10 For the fourth element two tubes are provided 63 and 64, the former for a spacing element, the latter for a marking element. The cathode circuit of tube 62 is accordingly connected to the control electrodes of both tubes 63 and 64. Similarly for each of the tubes 63 and 64 there is a pair of tubes 65, 66 or 67, 68 for the final element of the code.

The portion of Fig. 3 below the dashed line shows the additional tubes needed to extend the 20 arrangement to the receipt of eight codes, and from this it will be clear how the arrangement could be extended for the receipt of any number of codes permitted by the number of code elements used, that is 32 for a five-unit code. The letters placed in Fig. 3 opposite each tube for the final element of the code are the letters represented by the particular chain of devices that ends in that element.

In this way a complete teleprinter receiver may 30 be constructed, as shown in Fig. 4 which is composed of electric discharge devices, apart from the two receiving telegraph relays 16 and 17 and the relays such as 55 which can be arranged either to effect the printing of a character or to 35 perform any desired supervisory or indicating function. There are no rotating parts and mechanical wear is reduced to a minimum. The start tube 2 is shown in Fig. 4 and from this figure the connections of the remaining tubes will be 40 clear.

When a code combination is received, only that 45 chain of gas-filled tubes corresponding to the particular code combination is completed. Other chains are left in a condition in which one of the tubes other than the end tube of the chain is conducting when the receipt of the code combination comes to an end. All tubes that are thus left conducting are caused to become non-conducting when the tube 59 becomes conducting, 50 so that the equipment is ready to receive a subsequent code.

It should be noted that the multivibrator of 55 Fig. 2, may be set by means of the sliding contact on resistance 26 so that the relative periods during which it is in the respective conditions of stability are equal and this adjustment has been assumed in the foregoing description. In this condition of adjustment an impulse occurs on conductor 29 after the lapse of 10 milliseconds (assuming that the slider on resistance 25 is set for a total period of 20 milliseconds). The sliding contact on resistance 26 allows however of the adjustment of the initial period to suit distortion in the line 15, this adjustment corresponding to 60 that which is termed orientation adjustment with mechanical teleprinters. The impulses on conductor 29 follow one another after equal periods of time, the length of which depends on the frequency of the multivibrator, determined by the 65 adjustment of the sliding contact on resistance 25.

What is claimed is:

1. A receiver for predetermined telegraph codes comprising for each said code a chain of gas-filled electric discharge devices, one chain for 70 each element of the code; an electric impulse gen-

erator for generating a series of regularly repeated impulses, means for applying impulses from said generator to successive devices of said chains upon receipt of a code element of the required kind, means to apply an impulse from a preceding device in a chain simultaneously with said last named means, said successive devices in said chains adapted to be rendered conducting in accordance with the corresponding code element, means operative upon the last device in an operated chain becoming conducting to indicate the receipt of the code element, and means connected to each chain for restoring the devices thereof to non-conducting condition at the end of the period allotted to the receipt of the code.

2. A receiver as claimed in claim 1 comprising means for timing impulses from said impulse generator to occur at the mid-points of the period allotted to the receipt of successive elements of the code.

3. A receiver as claimed in claim 2 in which a pilot chain of gas-filled electric discharge devices is provided, one for each element of the code, comprising means for rendering said devices conducting successively, for periods equal to the periods of the successive elements of the code and means operative at the end of the period allotted to the receipt of a code combination for stopping said impulse generator and for restoring the receiver into a condition to receive a further code combination.

4. A receiver as claimed in claim 3, in which said means for generating electric impulses or said electric impulse generator comprises a multivibrator, and means for differentiating the changes of potential upon an electrode of said multivibrator to produce a series of impulses.

5. A receiver as claimed in claim 4 in which said pilot chain comprises one of said discharge devices normally in a conducting condition, means for impressing a first positive potential from said device upon a start device of said chain corresponding to the start element of a signal, disabling means for normally holding said impulse generator in one condition of stability, tele-
